EDWIN B. SINTZENICH, OF ROCHESTER, NEW YORK, ASSIGNOR TO HIMSELF AND HENRY G. HAMILTON, OF SAME PLACE.

Letters Patent No. 106,222, dated August 9, 1870.

IMPROVEMENT IN STEAM-GENERATORS.

The Schedule referred to in these Letters Patent and making part of the same.

I, EDWIN B. SINTZENICH, of Rochester, in the county of Monroe and State of New York, have invented certain Improvements in "Steam-Generators," of which the following is a specification.

My invention relates chiefly to a new arrangement of circulating-tubes in a steam-boiler, and the employment, in connection therewith, of thimbles, secured to the inner and outer shells, through which the circulating-tubes pass.

In the drawing—

Figure 1 is a vertical central section of an ordinary marine boiler, having my invention attached.

Figure 2 is a front elevation.

The circulating-tubes B B' pass centrally through the fire-flues A of the boiler, as fully described in my patent of February 21, 1865, and communicate with the water and steam-spaces at convenient points.

When, however, the tubes are attached directly to the shell of the boiler, as therein shown, their expansion and contraction, by alternate heating and cooling, soon loosens the joints or cracks the supporting-sheets. It is also a matter of difficulty to insert the tubes in a boiler already in use, or to obtain access to them for cleaning or repairs.

To obviate these difficulties, I provide, at points opposite the centers of the flues A, the thimbles c, of annealed tubing, passing through the water-spaces, and secured, similarly to any flue, to the inner and outer shells of the boiler. The internal diameter of these thimbles is such that the circulating-tubes slip easily through them, and the latter extend through the boiler and project somewhat at each end.

Branches a and d are attached to the tubes B B', which communicate with the water and steam-spaces of the boiler at convenient points, and the length of these branches allows the expansion of the tubes without injury to the connecting joints.

It will be observed that the introduction of the thimbles c is in no way deleterious to the boiler, but, on the contrary, they act as stays to the shell, while the connections a and d are easy of access for repairs, and the circulating-tubes may be readily cleaned by removing the plugs from their ends.

In the ordinary form of marine boiler shown in the drawing, the lower row of tubes, B', if carried through

the furnace similarly to the others, would interfere with the operations of the fireman, and I, therefore, bend them down in the rear of the grates, and connect them to the water-bottom F. This plan, I find, by experiment, to be very advantageous, since ordinarily the water in the furnace-bottom is never raised much above a blood-heat, while, by means of the bent tubes B', it is put into rapid circulation, and this part of the boiler soon becomes of the same temperature as the other portions.

It may be desirable to introduce the feed-water through the pipe D and branches D', directly into one or more of the circulating-tubes. By this means, such of the tubes as are exposed to the fire are somewhat cooled by the entering water, and the latter very soon heated to the temperature of that within the boiler.

In many cases, however, a deposit of calcareous or saline matter forms at the ends of the branches D', owing to the intense heat, and, for this reason, it is preferable to carry the pipes D' entirely through the circulating-tubes, and connect them to the shell of the boiler, as indicated by dotted lines f, fig. 1. The pipes D' thus become a heater for the water before it enters the boiler.

It is more convenient to attach the connections a and d to the outside of the boiler, but in many cases it may be preferable to attach them within, as shown in fig. 1, since additional heating-surface is thus utilized.

What I claim as my invention is:

1. The thimbles c, passing through the water-spaces of a steam-boiler, when used in connection with the circulating-tubes B, centrally located within the fire-flues, and connected to the water and steam-spaces of the boiler, substantially as described.

2. The arrangement of the bent tubes B' within the furnace and fire-flues of a steam-boiler, one end being connected to the water-bottom and the other to the water or steam-space of the boiler, substantially as and for the purposes set forth.

E. B. SINTZENICH.
